VALVE MEANS FOR INFLATABLE ARTICLES
James E. Gibson, Jr., 1005 Emery Road, High Point, N.C.
Filed Dec. 9, 1960, Ser. No. 74,932
5 Claims. (Cl. 137—223)

This invention relates to valve means for inflatable articles, and particularly to valve means of the type which are self-sealing whereby a needle can be removably passed therethrough for purposes of injecting air or other gas within the article.

Various types of inflatable articles, such as, for example, balls, are in common use today, and many of these articles are provided with valve means whereby gas can be introduced within the article for purposes of maintaining a proper inflation pressure. Such valve means which have been previously suggested may generally be classified in three groups: (a) that group which comprises complex arrangements incorporating spring devices or ball structures; (b) that group which incorporates a foldable or pluggable neck through which the breath of a human can be "blown" for inflation purposes; and (c) that group which comprises valve means having self-sealing characteristics whereby a needle can be passed therethrough for inflation purposes, and withdrawn therefrom without substantial leakage.

The first-mentioned group of valve means are necessarily expensive in manufacture, and for this reason alone present problems to the manufacturers of inexpensive inflatable articles. The second group, while inexpensive in manufacture and installation, is usable only on articles wherein the inflation pressure need be no greater than that which can be provided by a person "blowing the article up." The third group of valves presents somewhat the middle ground, in that such group in many instances is less expensive to manufacture than the first group, and serves to provide for maintenance of suitable inflation pressures. However, the third group still presents serious problems to the manufacturers of inexpensive items, and the present invention is directed to overcoming these problems.

The third group, which comprises the so-called "needle-type" self-sealing valves, usually includes structures comprising a valve casing with a valve member disposed therein. The prior constructions are such that a valve member is provided which has a substantially larger cross-section than an opening in the valve casing through which the valve member must be inserted. Thus, difficulty is encountered, and substantial time is required to insert the valve member within the valve casing or to place the valve member in operative position. Another problem which is encountered with the so-called "needle-type" self-sealing valves heretofore suggested is that the casings for the valve must be molded, in most instances, with an interior chamber which is larger, at least in part, than a small outlet passage provided in the casing. This presents molding problems because it is difficult to strip such casings from the molds. By virtue of the existence of both of these problems with the "needle-type" self-sealing valve, the expense of providing an inflatable article with the same becomes substantial, and manufacturers of inexpensive balls, for example, are, in many instances, forced to provide inflated structures without valve means. The inflated structures without valve means, due to the porosity of the material from which the structures are formed, eventually lose the inflation pressure by leakage through the article, and become useless. Moreover, without valve means, the structures are not re-inflatable articles, and thus when the manufacturer finds that the desired pressure is not provided in the article during its formation, due to some unexpected malfunction of the

2

inflating apparatus or components, the manufacturer is required to discard the article as unsatisfactory, having no way in which to cause proper inflation thereof after formation.

5 The primary object of the present invention is to provide a "needle-type" valve means for inflatable articles which is not subject to any of the disadvantages outlined above. More particularly, a primary object of the present invention is to provide a "needle-type" self-sealing valve which is simple in construction, formed from a minimum of parts, inexpensively fabricated and assembled, and readily attached to inflatable articles. Still further and more specific objects of the present invention are: (a) to provide an improved "needle-type" self-sealing valve means which can be easily incorporated on inflatable articles made with existing equipments; (b) to provide such a valve means which can be used whether external air pressure is used for purposes of inflating the article during formation or gas-liberating mediums within the preformed article are used for purposes of such inflation; (c) to provide such a valve means which comprises two easily-molded parts which can be readily stripped or removed from a mold; (d) to provide such a valve means which is readily adapted to incorporate, and does incorporate, a readily-deformable solid self-sealing means when high internal or inflation pressures are necessary; (e) to provide such a valve means comprising a valve casing and a valve member insertable within the casing, which valve member can be easily placed in operative position within the valve casing in a minimum of time and without the use of special tools; (f) to provide such a valve means which incorporates, if desired, a re-sealing slit in the valve member that facilitates pressing of the needle therethrough, and resealing after the needle is removed; (g) to provide such a valve means wherein all parts thereof can be pre-assembled whereby the valve means can be inserted within the inflatable article during its formation and prior to the final curing thereof; (h) to provide such a valve means which can be manufactured from available rubbers, vinyls, or urethane, or other easily-handled materials; and (i) to provide such a valve means which is trouble-free with continued operation.

45 In addition to the foregoing specific objects, it should be noted that one somewhat limited but important object of the invention is to provide an inexpensive valve means which can be easily incorporated on inexpensive items such as toy balls, whereby the need for producing inflated articles without a re-inflation valve is eliminated, and accordingly whereby the former loss encountered by manufacturers for such articles due to insufficient "forming pressures" becomes non-existent.

50 The invention lies in the construction, arrangement, and combination of the various parts of the valve assembly as will become apparent when consideration is given to the following detailed description of the illustrative and preferred embodiments of the invention shown in the annexed drawings, wherein:

55 FIGURE 1 is a cross-sectional view presenting a valve assembly constructed in accordance with the present invention, as the same would appear when installed on a inflatable article such as a ball;

60 FIGURE 2 is a cross-sectional view similar to FIGURE 1, but presenting a modified form of valve assembly constructed in accordance with the present invention, as the same would appear when installed on an inflatable article such as a ball;

65 FIGURE 3 is an exploded view of the assembly presented in FIGURE 1;

70 FIGURE 4 is an exploded view of the assembly presented in FIGURE 2;

FIGURE 5 presents in cross-section the assembly of FIGURE 1 as the parts of the same would appear when a needle has been passed therethrough for purposes of inflating the article with which the valve is used;

FIGURE 6 presents in cross-section the assembly of FIGURE 2 as the parts thereof would appear when an inflating needle has been passed through the assembly; and

FIGURE 7 is a cross-sectional view taken on the line 7-7 of FIGURE 1 and showing the concentric disposition of the assembly components.

In FIGURE 1, the valve means or assembly provided by the invention comprises a valve casing generally designated by the numeral 4 and an inner valve member generally designated by the numeral 6. The valve casing 4 includes a body section 8 within a conical or generally-conical chamber 10 therein which is closed at the smaller end 12 thereof. The casing also is provided with a base flange or section 14 projecting laterally of the body section 8 adjacent the larger lower end of the chamber 10.

The inner valve member 6 has a generally conical body portion 16 which is snugly receivable in the chamber 10. The inner valve member 6 also is provided with a base flange or portion 18 which mates with the underside of the base flange 14 of the casing 4. The valve member 6 has a bore 20 therein extending from the base portion 18 into the body portion 16 and terminating in spaced relation to the upper end 22 of the valve member.

The tubular body portion or section 8 of the casing 4 is preferably formed integrally with the base flange or section 14 from an elastomeric material, and similarly the inner valve member 6 is preferably formed as a continuous body from an elastomeric material. Moreover, the base flange or section 14 of the casing joins the body portion thereof contiguously whereby the chamber 10 is fully open at the lower end. The underside or lower face of the base portion 14 is, as shown, tapered inwardly toward the lower larger end of the chamber 10 whereby a peripheral recess or entry 24 is formed about the lower larger end of the chamber 10. This peripheral recess 24 is adapted to mate with the outwardly tapering upper face 26 of the base flange or section of the inner valve member 6.

The dimensions of the valve member 6, or at least of the body portion 16 thereof, are slightly larger than the corresponding inner dimensions of the chamber 10 according to the preferred embodiments of the invention. More particularly, at least the body portion 16 of valve member 6 is preferably slightly compressed to fit within the chamber 10. This feature is important because it provides for ready re-sealing of the valve member 6 after a needle has been passed therethrough, as explained in more detail below.

The preferred embodiment of the invention shown in FIGURE 1 also preferably includes a slit such as that designated by the numeral 28, which slit, as best shown in FIGURE 5, allows a needle 50 being inserted to pass between the opposed planar faces 50 and 52 thereof. These faces readily come together and meet smoothly to provide for improved re-sealing once the needle is removed and moreover, this construction facilitates insertion of the needle.

As also shown in FIGURES 1 and 5, the valve member 6 or body portion 16 thereof, terminates in spaced relation to the closed end 12 of the chamber 10 so as to provide a cavity 30 between the top 22 of the valve member and the closed end 12 of the casing. This cavity provides an air cushion above the valve member and also facilitates re-sealing.

The embodiment of FIGURE 1 is readily adapted for use in inflatable articles formed from vinyl or urethane, as well as for use in rubber articles. While various materials can be used for forming the assembly components, as explained hereinafter, it is important that the coefficient of elasticity of the material from which the casing is formed be greater than the coefficient of elasticity of the material from which the inner valve member 6 is formed and that the material from which the inner valve member

is formed have good re-sealing properties. The casing is an elastomeric body which serves to support the valve member properly, and to cooperate with the inner valve member for proper re-sealing. The inner valve members being formed of a softer material than the casing and having good re-sealing characteristics, allows the casing to press in on the valve body after the needle is removed to aid the re-sealing.

By reference to FIGURE 5 it will be noted that when a needle is inserted through the valve means, a puncture is made in the valve body 16 and in the closed end 12 of the casing. While the closed end of the casing tends to come back to closed position after the needle is removed, and thus tends to provide some re-sealing, the valve body 16 is, under the action of the pressures within the inflated article, pressed in. This pressure factor is in addition to the pressure factor applied by virtue of the differences in elasticity of the components, and both pressure factors coact to cause the walls of the casing to press in on the inner valve 6 or body portion 16 thereof, thereby causing the separated portions of the valve body to again flow together.

Aside from having the foregoing characteristics, the materials from which the components are formed should be such that the material used for the valve member 6 fusably softens at a higher temperature than the material used for the casing 4. This feature is important because it eliminates the possibility of fusion between the faces 50 and 52 of the slit 28 during curing of the article. When, for example, the article is plastic and cast in a rotatable type mold, the casing preferably softens and fuses with the material from which the inflatable article is formed, and yet no fusion of the slit faces is desired. Thus, by using materials having different fusible softening temperatures, the desired result is easily obtained. The term "fusably soften" as used herein refers to softening of the material to a state whereby adjacent components are joined or fused with the components in question.

While I have hereinabove described the preferred embodiment of the invention, the invention also provides as an equally-important, if not more important, embodiment, a valve assembly which is readily usable on articles wherein the inflation pressures are high, i.e., above approximately 3 lbs./in.². If reference is made to FIGURE 2, it will be noted that the valve assembly shown in such figure is generally the same as the valve assembly shown in FIGURE 1. It comprises a valve casing 4' and an inner valve member 6'. The casing 4', like the casing of FIGURE 1, comprises a body section 8' with an at least generally frusto-conical chamber 10' therein. The chamber is closed at the smaller end 12' thereof, and the casing is provided with a base flange 14' projecting laterally of the body section 10' adjacent the larger end of the chamber 10'.

The inner valve member 6' is elastomeric, like the casing 4', and is provided with a generally frusto-conical body portion 16' snugly receivable in the chamber 10'. The inner valve member 6' also includes a base portion or section or flange 18' mating with the base flange 14' of the casing. Similarly, the valve member 6' has a bore 20' therein extending from the base portion thereof toward the end 22' of the body portion remote from the base portion. The bore terminates in spaced relation to the end 22' of the valve member just as is the case with the bore in the embodiment of FIGURE 1. It will be noted that the bore 20' of the FIGURE 2 embodiment projects through a downwardly-extending nipple 30. This nipple terminates flush with the surface 32' of the inflatable article so that there is no depression adjacent the bore 20' like the depression, recess, or usual cut-out 33, which exists in the surface 32 of the material of the inflatable article shown in FIGURE 1. The casing of the embodiment of FIGURE 2 is formed in the same manner as the casing in the embodiment of FIGURE 1,

as is the inner valve member 6', and for this reason it is believed unnecessary to again reiterate the detailed slopes and mating cooperation between the components.

In the embodiment of FIGURE 1, the top end 22 of the valve member was shown as terminating in spaced relation to the closed end 12 of the casing. Similarly, in the embodiment of FIGURE 2, the top end 22' of the valve member 6' terminates in spaced relation to the closed end 12' of the casing 8'; however, preferably the cavity has a flat top as opposed to the curved top shown in FIGURE 1. In the embodiment of FIGURE 1, an empty cavity existed within this space, but in the embodiment of FIGURE 2 a body 40 is shown as disposed in such cavity and the flat top face facilitates action of this body as a resealing medium. The body 40 comprises a readily-deformable solid having excellent re-sealing properties, and preferably fills the entire cavity. When the needle 50 is inserted through the valve assembly of

5 can be completely and easily pre-assembled prior to being positioned in an uncured component of the final article. Moreover, the valve assemblies allow for inflation of the article during curing, either by using an external air pressure injected into the article through the assembly, or by using a gas-releasing pellet and a liquid catalyst therefor placed in the uncured article in conventional manner.

10 As suggested above, the materials from which the assembly components of either of the embodiments presented are formed, preferably have certain related fusible softening temperatures and coefficients of elasticity, and as is known to those of ordinary skill in the art, the materials of the assembly must be compatible with the materials from which the inflated articles are formed. I have found that the best operating results are obtained when the materials are selected in accordance with Table I.

Table I

Article material	Casing (4 or 4') material	Valve member (6 or 6') material	Gasket (body 40) material
Rubber.....	Natural rubber (70 Shore A hardness).	Natural rubber (40-45 Shore A hardness).....	Uncured natural milled rubber.
Vinyl or urethane (polyurethane).	Vinyl or nitrile rubber (e.g., butadiene-acrylonitrile).	Soft vinyl (e.g., plasticized vinylchloride) or sulphurless rubber (e.g., unvulcanized natural or synthetic rubber) or silicone rubber (e.g., a polymeric dimethyl siloxane rubber).	Do.

FIGURE 2, as shown in FIGURE 6, then the readily-deformable solid is easily displaced. When the needle is removed from the assembly, the readily-deformable solid material 40 readily re-seals, blocking the valve member 6' substantially from any pressure entering through the opening which may be left in the closed end 12' of the casing. The valve member 6' of course serves as an effective seal and has self-sealing properties itself which are aided by the inward compression exerted by the walls of the casing 8'. However, the FIGURE 2 embodiment is found particularly desirable in instances where high inflation pressures must be maintained, because, as should be apparent, the readily-deformable solid material 40 provides a more positive seal than the air cavity 30 shown in FIGURE 1.

In both the embodiment of FIGURE 1 and the embodiment of FIGURE 2 the valve chamber is continuously conical or frusto-conical, as is the body of the valve member. While the valve member is preferably slightly larger than the chamber is in corresponding cross-section, the valve member can easily be inserted in the chamber. The construction of the invention thus eliminates the insertion problems heretofore existent because there is no need for passing a large portion of the valve member through a substantially smaller opening in the valve casing. Moreover, both components are so shaped that they can be molded in simple cavity-type molds and easily "stripped" therefrom.

While the readily-deformable solid body 40 is only shown in FIGURE 2, it is to be understood that such body can be readily incorporated in the cavity of FIGURE 1, if desired. It has been found that when the inflation pressures within the article with which the assembly is used are above 3 p.s.i., the provision of body 40 is particularly advantageous to ensure prolonged inflation pressure maintenance. However, pressures this high can be used without the inclusion in the assembly of the readily-deformable body without departing from the scope and spirit of the invention.

The method of forming the inflatable article has not been described in detail hereinabove; however, it will be readily apparent to those of ordinary skill in the art that the valve assemblies provided by the invention are readily adapted to be used and positioned in accordance with existing techniques, and that the valve assemblies

35 When the foregoing materials are used for production of inflatable rubber articles, then the valve assembly provided can be adhered in place in accordance with conventional practice during the pre-forming operation by a rubber cement. When the foregoing materials are used for the production of vinyl or urethane articles then a vinyl plastisol can be used for proper preliminary adherence in a conventional manner.

40 One particular advantage of the suggested materials of the assembly for use in the vinyl or urethane articles is the fact that these materials result in a homogenous fusing between the valve casing and the surface of the article to which such casing is attached, e.g., as at the point 60 in FIGURE 1.

45 After reading the foregoing detailed description of the preferred and illustrative embodiments of the invention, it will be apparent that the objects set forth at the outset of this specification have been successfully achieved, and that various modifications may be made to the embodiments explained in detail which do not depart from the scope and spirit of the invention. Accordingly, what is claimed is:

- 55 1. A valve means for inflatable articles comprising a valve casing having an elastomeric tubular body portion with a hollow generally frusto-conical chamber therein closed at the smaller end, and an integral base portion extending laterally of said body portion, the upper face of said base portion contiguous with said body portion being tapered outwardly and away from said body portion, said base portion having an aperture contiguous with the larger end of said chamber, the lower face of said base portion having a recess tapered inwardly toward said aperture; and a valve member comprising an elastomeric body section adapted to be snugly received inside said tubular body portion of said casing, and a valve base section extending laterally of said valve body section, the upper surface of said valve base section contiguous with said valve body section being tapered outwardly and away from said body section, said upper surface of said valve base section mating with said recess in said lower face of said casing base portion, said body section of said valve member normally having outward dimensions slightly greater than the corresponding inner dimensions of said chamber, said valve member having a bore therein extending from the lower face thereof to a

point within said body section spaced from the end of said body section nearest the closed end of said chamber, whereby a needle can be substantially freely inserted in said recess and then pressed through said valve member and the closed end of said casing and thereafter removed from said valve means, and whereby when the needle is removed from said valve means, said body portion of said casing presses on said valve member body section to close the opening therein made by the needle.

2. A valve means as defined in claim 1 wherein said casing is formed from a different material than said valve member, and wherein the material from which said casing is formed fusably softens at a lower temperature than the material from which said valve member is formed.

3. A valve means as defined in claim 1 wherein said valve member body section terminates in spaced relation to the closed end of said chamber to provide a cavity between said valve member and said closed end, and wherein said valve member body section is split longitudinally in the portion thereof adjacent said cavity to

provide two normally engaging planar faces between which an inflation needle can pass when pressed through said body section.

4. A valve means for inflatable articles as defined in claim 1 wherein said casing and said valve member are formed from different materials and the coefficient of elasticity of the material from which said casing is formed is greater than the coefficient of elasticity of the material from which said inner valve member is formed.

5. A valve means as defined in claim 1 wherein the material from which said valve member is formed has natural resealing characteristics.
